US0D1048461S

(12) **United States Design Patent** (10) **Patent No.:** **US D1,048,461 S**
(45) **Date of Patent:** **** Oct. 22, 2024**

(54) **INSTRUMENT**

- (71) Applicant: **Meso Scale Technologies, LLC.**, Rockville, MD (US)
(72) Inventors: **Jacob N. Wohlstadter**, Palm Beach Gardens, FL (US); **Roger Darin Osborne**, Stuart, FL (US); **Sandor Kovacs**, Middletown, DE (US); **Aaron Leimkuehler**, Upper St Clair, PA (US); **Cecilia Zimmerman**, Clarksburg, MD (US); **Jules VanDersarl**, Gaithersburg, MD (US)
(73) Assignee: **MESO SCALE TECHNOLOGIES, LLC.**, Rockville, MD (US)

(**) Term: **15 Years**

(21) Appl. No.: **29/926,279**

(22) Filed: **Jan. 30, 2024**

Related U.S. Application Data

- (60) Continuation of application No. 29/901,082, filed on Aug. 29, 2023, now Pat. No. Des. 1,016,325, which is a continuation-in-part of application No. 29/786,021, filed on May 28, 2021, now Pat. No. Des. 999,398, which is a division of application No.

CLAIM

The ornamental design for an instrument as shown and described.

DESCRIPTION

FIG. 1 is a front perspective view of an instrument showing our new and ornamental design;

FIG. 2 is an alternate front perspective view thereof;

FIG. 3 is an alternate front perspective view thereof;

FIG. 4 is an alternate front perspective view thereof;

FIG. 5 is a front elevation view thereof;

FIG. 6 is a side elevation view thereof;

FIG. 7 is a side elevation view thereof;

FIG. 8 is a top plan view thereof;

FIG. 9 is a rear elevation view thereof;

FIG. 10 is a rear perspective view thereof; and,

FIG. 11 is a bottom rear perspective view thereof.

The broken lines illustrate portions of the instrument that form no part of the claimed design.

1 Claim, 11 Drawing Sheets
